UNITED STATES PATENT OFFICE

OTTO E. TRAUTMANN, OF ROCHESTER, NEW YORK, ASSIGNOR TO BAUSCH & LOMB OPTICAL COMPANY, OF ROCHESTER, NEW YORK, A CORPORATION OF NEW YORK

DESIGN FOR A COLORIMETER LAMP

Application filed November 11, 1929. Serial No. 33,414. Term of patent 14 years.

To all whom it may concern:

Be it known that I, OTTO E. TRAUTMANN, a citizen of the United States, and a resident of Rochester, county of Monroe, and State of New York, have invented a new, original, and ornamental Design for Colorimeter Lamp, of which the following is a specification, reference being had to the accompanying drawing, forming a part hereof.

The figure shows a perspective view of a colorimeter lamp showing my new design. The structure of the opposite side of the lamp is identical with that shown in the foreground.

I claim:

The ornamental design for a colorimeter lamp substantially as shown and described.

OTTO E. TRAUTMANN.
